DEMOUNTABLE FRONT FOR FULLING MILLS

Warren J. Simonds, Orange, and Roswell C. Jefferson, Greenfield, Mass., assignors to Rodney Hunt Machine Company, Orange, Mass., a corporation of Massachusetts

Application January 3, 1938, Serial No. 183,089

4 Claims. (Cl. 26—20)

This invention relates to a device in the form of a top front end for a fulling mill which is movable on the fulling mill itself in a very easy manner to uncover the top rolls to enable them to be re-jagged, turned down, or dismantled.

The principal other objects of the invention are to provide this top front end in such a form that it can be fixed to the rest of the frame, very readily detached therefrom with equal facility, held in position on the fulling mill while repairs are being made, and set back into accurate position with a single motion ready to be fastened in place to put the fulling mill into position for proper operation.

15 Other objects and advantages of the invention will appear hereinafter.

Reference is to be had to the accompanying drawing, in which

Fig. 1 is a side view of an ordinary fulling mill showing a preferred form of this invention with the top front end drawn back away from the top rolls to expose them for repair or replacement, and

Fig. 2 is a similar view, showing the top front end brought back into operative position and fastened to the fulling mill.

Most of the fulling mills in use are equipped with wood lagged rolls. These very often have to be turned down and also have to be re-lagged. 30 They even have to be taken out and repaired in other ways. Heretofore, it has been necessary entirely to dismantle the top of the mill before any of these operations could be performed. The mere dismantling and disconnecting the parts 35 takes from fifteen to twenty-five hours.

By this invention the rolls can be exposed and can be removed from the machine, if necessary, in approximately one-tenth the time heretofore occupied by this machine. Also the demountable front end permits access to the rolls as they are mounted in the machine. Hence it is now possible to re-lag rolls and refinish them right in the machine without danger of replacing them incorrectly and without the necessity of removing them. Incidentally also either one of the rolls can be repaired or removed without disturbing the other roll which is a distinct advantage. If there are any other repairs necessary to the metal work of the roll, it can be accomplished more easily.

In the form in which the invention is illustrated, an ordinary fulling mill 10 is employed having the top rolls 11 and 12 supported on brackets 13 and 14 at both ends. These brackets 55 are secured to the framework at one end, they

carry the axles of the rolls and at the other end they are secured, as shown in Fig. 2, to the demountable top front end 15 when the machine is in use, as shown in Fig. 2.

The frame of the machine is provided with a platform 16 located in permanent position and extending out to the front of the machine. This may be supported by struts 17 or vertical supports 18 or both, as shown. This platform furnishes a track for two pairs of rollers 19 on the bottom of the end 15. Also on the body of the frame of the fulling mill 10 are located tracks 20, preferably convex in cross section for the rollers 19 which, preferably, are grooved rollers. This track is provided with two notches 21 and, of course, there is such a track on each side of the machine. 5 10 15

When it is desired to re-lag, repair, or remove one or both of the rolls 11 and 12, the fastening devices are removed from the brackets 13 or 14 20 and the end 15 is moved back. Of course, the first action is to lift the rollers 19 out of the notches 21 and this is ordinarily done by a pinch bar. The end is then rolled on the platform 16, the repairs made, the end 15 moved back 25 where the rollers 19 sink into the notches 21. These notches not only serve to prevent the end 15 from rolling again before it is fastened but they serve as the supports for it.

It will be noticed that the end 15 has a horizontal projection at 23 at each end which, when the parts are in operative position, passes over a complementary projection 24 on each side of the fuling mill. It is not intended that these surfaces constitute a rest to take away any of the weight of the ends. 35

In this way it will be seen that this demountable front end is a distinct saving because, after the machine is erected, the front end does not have to be dismantled, as has been the case heretofore. It can be moved simply as a unit. Furthermore, the customer can quickly erect it in his mill, which is a direct saving in labor and eliminates the need of adjustments. Otherwise adjustments are made at the factory at the time of the first erection. The moving of this end back as shown in Fig. 1 leaves the operator full access to the rolls and any operation desired can be performed on them, often without moving them at all and avoiding the necessity of taking down the whole equipment.

Having thus described our invention and the advantages thereof we do not wish to be limited to the details herein disclosed, otherwise than as set forth in the claims, but what we claim is: 55

1. As an article of manufacture, a fulling mill having a pair of rolls at the top one over the other and provided with a detachable top front end covering the side surface of these rolls and capable of being moved bodily away from them horizontally to expose them for repairs or dismantling.
2. In a fulling mill, the combination with rolls, of a top front end adapted to cover said rolls and detachable therefrom, a platform beyond the end of the fulling mill and supporting rollers on the top front end by which the latter can be moved from normal position horizontally on the platform to expose said rolls.
3. In a fulling mill, the combination with the rolls, of a top front end normally covering them, detachable means for fastening the front end in position to cover the rolls, a platform for receiving the top front end, rollers for supporting the top front end on the platform, and tracks on the fulling mill fitting said rolls and having recesses into which the rollers will sink when the top front end is moved up to operative position and which will prevent said end from moving while being fastened in place.
4. In a fulling mill, the combination of a top front end, a platform for receiving the top front end, rollers for supporting the top front end on the platform, and tracks on the fulling mill having recesses into which the rollers will sink when the top front end is moved up to operative position and which will prevent said end from moving while being fastened in place.
